CLAIM

The ornamental design for a lighted welding helmet, as shown and described.

DESCRIPTION

FIG. 1 is a front view of a lighted welding helmet showing my new design.

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines appearing on FIGS. 2, 5 and 6 are of environmental matter forming no part of the claimed design.
